(57) **CLAIM**

The ornamental design for a winch adapter platform, as shown and described.

DESCRIPTION

FIG. 1 is a side elevation of a winch adapter plate showing my new design;

FIG. 2 is a bottom plan view;

FIG. 3 is a right side elevational view;

FIG. 4 is a top plan view;

FIG. 5 is a front elevational view;

FIG. 6 is a perspective view mounted on a truck hitch supporting a winch with a wire line shown in broken outlines;

FIG. 7 is a rear elevational view; and,

FIG. 8 is a perspective view mounted on a tree shown in phantom outline.

The broken line showing of a ratched strap, truck, tree and winch in the figures is for illustrative purposes only and forms no part of the claimed design.
